(57) **CLAIM**

The ornamental design for a weighted swing training apparatus, as shown.

DESCRIPTION

The present application is related to U.S. Pat. No. D669,142, filed Aug. 11, 2011, entitled “Weighted Swing Training Apparatus,” and to U.S. Design patent application Ser. No. 29/500,634, filed Aug. 27, 2014, entitled “Weighted Swing Training Apparatus.”

FIG. 1 is a perspective view of a weighted swing training apparatus showing my design;

FIG. 2 is a front elevational view of the weighted swing training apparatus;

FIG. 3 is a rear elevational view of the weighted swing training apparatus;

FIG. 4 is a left side elevational view of the weighted swing training apparatus;

FIG. 5 is a right side elevational view of the weighted swing training apparatus;

FIG. 6 is a top plan view of the weighted swing training apparatus; and,

FIG. 7 is a bottom plan view of the weighted swing training apparatus.

The claimed weighted swing training apparatus may be used coupled to a baseball or softball bat, for example, for warm-up and practice swings.

1 Claim, 4 Drawing Sheets
